UNITED STATES PATENT OFFICE.

GEORGE W. BLAIR, OF PITTSBURG, PENNSYLVANIA.

DESIGN FOR A LAMP-CHIMNEY.

SPECIFICATION forming part of Design No. 29,881, dated December 27, 1898.

Application filed December 1, 1898. Serial No. 698,011. Term of patent 7 years.

To all whom it may concern:

Be it known that I, GEORGE W. BLAIR, of Pittsburgh, in the county of Allegheny and State of Pennsylvania, have invented a new and original Design for Lamp-Chimneys, of which the following is a full, clear, and exact description, reference being had to the accompanying drawing, which shows in side elevation a gas-lamp chimney embodying my design.

In the drawing 2 represents the body of the lamp-chimney, having at its upper portion a shoulder 3, and above said shoulder a tapering portion 4, which is crimped at the upper end.

The leading feature of my invention consists in a lamp-chimney having the features above enumerated—namely, a body portion, a shoulder at the upper portion of the body, and a neck portion having a crimped top. 20

I claim—

The design for a chimney, substantially as herein shown and described.

In testimony whereof I have hereunto set my hand.

GEORGE W. BLAIR.

Witnesses:

THOMAS W. BAKEWELL,
G. I. HOLDSHIP.
